UNITED STATES PATENT OFFICE.

HENRY HIGGIN, OF NEWPORT, KENTUCKY, ASSIGNOR TO THE HIGGIN MANUFACTURING COMPANY, OF SAME PLACE.

BAND-SHELL FOR WHEEL-HUBS.

SPECIFICATION forming part of Letters Patent No. 624,935, dated May 16, 1899.

Application filed April 15, 1898. Serial No. 677,718. (No model.)

To all whom it may concern:

Be it known that I, HENRY HIGGIN, a citizen of the United States, residing at Newport, in the county of Campbell and State of Kentucky, have invented certain new and useful Improvements in Band-Shells for Wheel-Hubs, of which the following is a specification.

The object of my invention is to provide a band-shell which is automatically secured to an ordinary hub-band by being forced there-over; and the invention consists in the novel band-shell hereinafter described and claimed.

In the drawings, Figure 1 is a side elevation of my band-shell as applied to a hub. Fig. 15 2 is a longitudinal section of the same.

A represents a wheel-hub, B a hub-band, and C a band-shell.

The band-shell C is made of a size and shape which will fit the band somewhat snugly, but which will also permit it to be slipped onto the band and driven nearly home by comparatively slight pressure, such as may be exerted by hand, which may be supplemented by use of a driver, which enables it to be completely driven home by use of an ordinary mallet, and is provided near its inner end with a nipping edge or shoulder c, which projects inwardly from its inner surface and tightly grips the surface of the hub-band when the band-shell is placed in position. From the nipping edge c the portion c' flares outwardly, so as to make the mouth of the band-shell C slightly funnel-shaped. The effect of this arrangement is that as the band-shell C is forced over the hub-band B the bevel caused by the flare of the portion c' allows the edge c to easily slip over any irregularities in the surface of the hub-band B; but the edge or shoulder c acts as a barb to resist its removal.

40 I prefer to form the edge or barb c by stamping at the desired place in the band-shell C an annular groove or bead c² and extending the inner side thereof until it projects from the normal inner surface of the band-shell, as shown in Fig. 2.

In order to render the portion c' more flexible, so that it will more easily pass over irregularities or obstructions on the rough castings, I prefer to corrugate it, as shown at c³ in Fig. 1. This corrugation or knurling also

serves as an ornamental finish for the inner end of the band-shell.

When the band-shell is placed in position before the paint on the hub is thoroughly dry, the edge c sinks therein, so that when the 55 paint becomes dry and hard it holds the shell securely locked in position.

I am aware that band-shells have been made of slightly-smaller diameter than the outer diameter of the band and forced onto the band 6c by hydraulic pressure, thereby expanding the shell and causing it to grip the band; but this plan is objectionable, not only because it requires power apparatus to force it on, but because the shells frequently burst under the 65 pressure.

My improved shells can be placed on the band by hand quickly and with but slight effort, and experience shows that they retain their position so firmly that there is no danger of accidental displacement and very considerable force is required to remove them. 70

I claim—

1. A band-shell having a nipping edge, extending inwardly beyond the normal inner 75 surface of the shell, adapted to automatically grip the hub-band as the band-shell is forced into position, substantially as and for the purpose set forth.

2. A band-shell having an outwardly-extending annular groove, the inner edge of which projects inwardly beyond the normal inner surface of the band-shell, substantially as and for the purpose set forth. 80

3. A band-shell having a nipping edge extending inwardly beyond the normal inner surface thereof, and having a portion between the nipping edge and its inner end, flared to form a bevel, substantially as and for the purpose set forth. 85

4. A band-shell having an outwardly-extending annular groove, the inner edge of which projects inwardly beyond the normal inner surface of the band-shell, said shell having a portion between the groove and the inner end of the shell, flared to form a bevel, substantially as and for the purpose set forth. 90

5. A band-shell having a nipping edge projecting inwardly beyond the normal inner surface thereof, and having a portion between the 95

nipping edge and the inner end of the shell, corrugated to increase the flexibility thereof, substantially as and for the purpose set forth.

6. A band-shell having a nipping edge projecting inwardly beyond the normal inner surface thereof, and having a portion between the nipping edge and the inner end of the shell, flared to form a bevel and corrugated to increase the flexibility thereof, substantially as and for the purpose set forth.
- 5 7. A band-shell having an outwardly-ex-

tending annular groove, the inner edge of which projects inwardly beyond the normal inner surface of the shell, and having a portion between the groove and the inner end of the shell flared to form a bevel and corrugated to increase the flexibility thereof, substantially as and for the purpose set forth. 15

HENRY HIGGIN.
